Frank J. Kent

UNITED STATES PATENT OFFICE.

WILLIAM H. STEVENS, OF NEW YORK, N. Y.

GARTER.

Specification of Letters Patent. Patented Jan. 27, 1920.

1,328,931.

Application filed July 17, 1917. Serial No. 180,990.

To all whom it may concern:

Be it known that I, WILLIAM H. STEVENS, a citizen of the United States, residing at New York, in the county of New York and State of New York, have invented certain new and useful Improvements in Garters, of which the following is a specification.

This invention relates to improvements in garters, and one of the objects is to provide an attaching member for garters of such construction that it will securely hold the fabric of the stocking or garment and without danger of tearing.

A further object is to provide a construction of garter including a novel attaching means whereby the garter is adapted for use either as a side garter or a leg garter.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawings, which are to be taken as part of this specification, and in which I have shown merely a preferred form of embodiment of the invention, Figure 1 is an elevation of a combined leg and side garter, showing it disposed for use as a leg garter; Fig. 2 is an elevation of the subject-matter of Fig. 1 disposed for use as a side garter; and Fig. 3 is a perspective view illustrating the form of attaching member illustrated in Figs. 1 and 2.

Referring to the numerals on the drawings and particularly Figs. 1 and 2, there is shown at 16 a garter which comprises a relatively long portion and a shorter length 17 connected together by means of a ring 18. At the free end of the longer portion 16 of the garter there is an attaching member indicated by the numeral 19, and shown in detail in Fig. 3. This attaching member comprises a flat frame, having an extensive cut-out portion 20 diminishing into a relatively curved slot 21. Adjacent the cut-out portion 20 the frame is formed with a hook member 22, which is merely a portion of the frame bent over. When the garter is to be used as a leg garter the frame 19 is turned on the looped end 24 of the length 16 so that the looped end of the length 16 en-

gages in the curved slot 21, while the hook portion 22 is presented for engagement with the ring 18. If the garter is to be used as a side garter the frame 19 is turned on the looped end of the length 16 of the garter until the hooked end 22 is held within the loop 24 and the slotted end 21 is presented for engagement with the stocking or garment. Whether the garter is used as a leg garter or a side garter the end of the short length 17 will of course be provided with a member 25 for engagement with the stocking or garment. Preferably the portion of the frame 19 which carries the hook 22 is straight so that the looped end 24 of the garter will be properly spread; the same result is accomplished of course by the curved slot 21 when the garter is used as in Fig. 1.

When the garter of Figs. 1 and 2 is used as a side garter the attaching member 19 is engaged with the stocking in the same way as the attaching member 25 shown in Fig. 1, that is to say, a bight of the fabric of the stocking or garment is pulled through the cut-out 20 and then allowed to drop down within the curved slot 21, where it spreads and is held by its engagement with the edges of the slot.

It will be understood that the various attaching members shown in the drawings can be made of different materials; in some cases metal will be used and in others celluloid or the like. Of course care should be taken to have the gripping edges in every case rounded or smoothed so as to avoid tearing of the garment.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

I claim:

1. A combined side and leg garter comprising a short and a long length of material, a joint member pivotally connecting the lengths of material at one end thereof, respectively, an attaching member on the other end of the short length of material, and an attaching member on the other end of the long length of material and rotatably supported with relation thereto so that it may be turned end-for-end thereon, one end

of the last named attaching member being provided with a part for engagement with a garment when the device is used as a side-garter, and the other end provided with a part for engagement with the joint member between the two lengths of material, when the device is used as a round-the-leg garter.

2. A device as described in claim 1, in which the joint member is a ring and in which the last named attaching member is provided with a garment engaging part on one end and with a hook on the other end.

3. A device as described in claim 2, in which the last named attaching member is a piece having a top cross-bar, with a hook

projecting therefrom, the piece below the bar being provided with an opening gradually diminishing in width toward one side of the piece and continuing at the bottom of the piece as a slot, and thence curved upwardly, whereby is formed a tongue integral with the piece and defined by the opening and the slot; and in which the long length of material has a loop end in which the piece is held so that it may be turned end-for-end, substantially as and for the purpose set forth.

In testimony whereof I affix my signature.

WM. H. STEVENS.
